US00D742915S

(12) United States Design Patent
MacLean

(10) Patent No.: US D742,915 S
(45) Date of Patent:  Nov. 10, 2015

(54) DISPLAY SCREEN OR PORTION THEREOF
WITH ICON

(71) Applicant: Apple Inc., Cupertino, CA (US)

(72) Inventor: Alexander Charles MacLean, San Jose, CA (US)

(73) Assignee: Apple Inc., Cupertino, CA (US)

() Term: 14 Years

(21) Appl. No.: 29/494,778

(22) Filed: Jun. 24, 2014

Related U.S. Application Data

(63) Continuation of application No. 29/413,013, filed on Feb. 9, 2012, now Pat. No. Des. 709,095.

(57) CLAIM

The ornamental design for a display screen or portion thereof with icon, as shown and described.

DESCRIPTION

FIG. 1 is a front view of a display screen or portion thereof with icon showing my new design.

The broken lines around the FIGURE show a display screen or portion thereof, and form no part of the claimed design.

1 Claim, 1 Drawing Sheet
